UNITED STATES PATENT OFFICE.

ARTHUR A. MERRITT, OF WORCESTER, MASSACHUSETTS, ASSIGNOR TO WILLCOX & GIBBS SEWING MACHINE CO., OF NEW YORK, N. Y., A CORPORATION OF NEW YORK.

TENSION-THREAD GUIDE.

Application filed May 11, 1920, Serial No. 380,514. Renewed February 7, 1923.

To all whom it may concern:

Be it known that I, ARTHUR A. MERRITT, a citizen of the United States, and a resident of Worcester, Massachusetts, have invented 5 new and useful Improvements in Tension-Thread Guides, which invention is fully set forth in the following specification.

This invention relates to thread tension guides usable wherever it is desirable to impose tension upon a thread in guiding the same from one point to another, but designed especially for use in feeding threads from cones or bobbins to power operated sewing machines in factories or mills. For 10 example, in the operation of the machine known commercially as the Willcox & Gibbs Sewing Machine Company's "flatlock machine," shown, for example, in the patent to A. A. Merritt, No. 1,041,652, dated October 20 15, 1912, the four looper threads, four needle threads, and one cross-thread—nine threads in all—are supplied from nine cones or bobbins respectively. These thread cones are mounted on a stand, each thread being led 25 upward from its cone through an overhanging thread guide on the stand, thence in a downward direction to a thread eye of the machine, and thence between tension disks of the tensioning mechanism of the machine. 30 It has been found by experience that kinks or loose loops occur quite frequently especially in thread which is dry or which has a considerable twist, and such kinks or loops, if not straightened out, will get to and be 35 tween the tension disks or plates and be there held as a knot resulting in breaking of the thread at the needles or elsewhere at some point between the tension plates and the point where the thread should be set in 40 the fabrics seam. Thus, these kinks or loops act with the same effect as knots and are just as troublesome in interfering with and interrupting the operation of the machine.

An object of the present invention is to 45 straighten out such kinks or loose loops before the same can reach the tension mechanism of the sewing machine and preferably directly after the thread leaves its cone. This I am enabled to accomplish by passing 50 the thread from the cone through a thread tension guide of the present invention by which a slight tension may be applied to the thread to straighten out kinks or loose loops before the thread reaches the sewing 55 machine.

It has also been found desirable in the operation of said flatlock machine, for the purpose of assuring evenness of appearance on the underside of the seam formed thereby, to provide extra tensioning means for 60 individually and separately tensioning some one or more of the threads, particularly the four needle threads, to attain a tension balance between the four rows of stitches such as cannot always be attained by adjustment 65 of the regular tension means of the machine in which the tension plates of each group of such plates are pressed together by means common to all of the plates of the group. Use of thread tension guides of the present 70 invention enables each thread to be tensioned independently of other threads.

Still other objects are attained as will be apparent from the accompanying drawings and detailed description of what is now regarded as the preferred embodiment of the 75 invention.

In said drawings—

Fig. 1 is a view in elevation; Fig. 2 is a longitudinal section on line 2—2 of Fig. 1;

Figs. 3 and 4 are detailed views of the fixed and adjustable members of the device respectively;

Fig. 5 is a view in elevation of a slightly 85 modified form; and

Fig. 6 is a view showing the device positioned on a thread stand between a thread cone and a thread guide on a sewing machine.

The thread tension guide of this invention comprises a fixed member or stem part 10 and a movable adjustable sleeve member or thimble 15.

At one end stem 10 is screw-threaded for 95 engagement with any suitable support; at its other end it has cylindrical portions 11 and 12 of slightly different diameters; and between said end portions there is a cylindrical portion 13 with a large thread eye 100 or passage 14 therethrough. The adjustable member 15 has a cylindrical outer surface; at one end it has a knurled enlargement or head 16 and at its inner end it is bored out to form a sleeve portion 17 adapted to telescope over the outer end of the fixed stem up to the shoulder 18 thereof. The boring of the sleeve is such that its interior diameter is slightly smaller at the outer end of the sleeve at 19 than at the inner end thereof 110

at 20, this difference of interior dimensions of the sleeve substantially conforming to the variation of exterior dimensions of the parts 11 and 12 of the outer end of the stem over which the sleeve fits. The sleeve has three equidistant longitudinal slits or slots 21, enabling the sleeve to slightly expand and contract in forcing it on to the stem and in engaging said stem with friction sufficient to 10 retain said sleeve in any position of adjustment to which it is rotated. A large thread eye or passage 22 extends diagonally through the outer end of the adjustable sleeve member 15, one end thereof being positioned in 15 the cylindrical side wall of said member and the other end in the center of the end wall of head 16.

In Fig. 1, the thread 23 is shown as passing upward from any suitable source of supply through thread eye 22, thence spirally approximately one and one-half times around the cylindrical surface of the device and through thread eye 14, and thence in a downward direction to a sewing machine not shown. The passage of the thread along and around the cylindrical surface between the thread eyes increases the friction and hence the tension on the thread in its passage through the device, and it is obvious 30 that by gripping the knurled head 16 and turning adjustable member 15 on the fixed stem member 10 toward the left in Fig. 1, the spirality of the path of the thread may be decreased and the friction and tension 35 upon the thread correspondingly lessened. The opposite effect may be obtained by a reverse adjustment of the member 15, that is by turning it toward the right in Fig. 1.

By the use and adjustment of such a tension thread guide the desired tension may be imposed upon a thread to straighten out kinks or loose loops in drawing the thread from a cone, bobbin, or the like, or to adjust the tension to that required for proper 45 stitch or seam formation, or for other purpose.

In the modified structure of Fig. 5 a slot 24 leads into the thread-eye or passage 25; in other words, an open thread eye is provided in place of the closed thread-eye 14 of Figs. 1 and 2.

Fig. 6 shows a thread cone 26 mounted on a thread stand (only part of which is shown), the thread being led upward from the cone through a tension thread guide of the present invention supported by an overhanging arm of the stand, thence downward through a thread guiding plate 28 and between tension plates 29. Said plate 28 corresponds to plate 657, and said tension plates 29 to similar plates 653, of Fig. 52 of the aforesaid Merritt Patent 1,041,652 on the aforesaid flatlock machine of the Willcox & Gibbs Sewing Machine Company. 65 There is thus interposed between the thread

cone and the sewing machine a tension thread guide which may be adjusted to impose upon the thread suitable tension for straightening out kinks or loose loops before the same can reach the tension plates 70 of the machine and a tension such as required for that particular thread in the formation of the stitch or seam of which it becomes a part.

What I claim is:—

1. In a tension thread guide, a stem member having a thread-eye, and adapted to be attached at one end to a support and a sleeve member also having a thread-eye and embracing the free end of said stem and having rotatable adjustment thereon, said members providing a surface along which the thread passes from one of said thread-eyes to the other in a more or less spiral path variable to increase or decrease the tension upon the thread by rotatably adjusting the sleeve member on the stem. 75

2. In a tension thread guide, a fixed stem member having a thread-eye, and a sleeve member also having a thread-eye and embracing a portion of said stem of reduced diameter and having rotatable adjustment thereon, said members providing a surface along which the thread passes from one of said thread-eyes to the other in a more or less spiral path variable to increase or decrease the tension upon the thread by rotatably adjusting the sleeve member on the stem. 90

3. In a tension thread guide, a fixed stem member having a thread-eye, and a cylindrical adjustable member also having a thread-eye and at one end thereof a spring socket portion frictionally embracing but rotatively adjustable on a cylindrical end portion of the stem member, said members providing a surface along which the thread passes from one of said thread-eyes to the other in a more or less spiral path variable to increase or decrease the tension upon the thread by rotatably adjusting the sleeve member on the stem. 100

4. In a thread tension guide, a fixed stem member having a thread-eye therethrough, and a relatively adjustable cylindrical member also having a thread-eye therethrough and socketed in one end to form a sleeve portion frictionally embracing a cylindrical end portion of the stem and rotatively adjustable thereon, said members providing a surface along which the thread passes from one of said thread-eyes to the other in a more or less spiral path variable to increase or decrease the tension upon the thread by rotatably adjusting the sleeve member on the stem. 115

In testimony whereof I have signed this specification.

ARTHUR A. MERRITT.
